UNITED STATES PATENT OFFICE.

JOHN A. AMOS, OF ST. LOUIS, MISSOURI, ASSIGNOR TO OLIVER ELECTRIC AND MANUFACTURING COMPANY, OF ST. LOUIS, MISSOURI, A CORPORATION OF MISSOURI.

DESIGN FOR A LAMP CASING.

Application filed June 9, 1924. Serial No. 9,835. Term of patent 14 years.

To all whom it may concern:

Be it known that I, JOHN A. AMOS, a citizen of the United States of America, residing at the city of St. Louis, State of Missouri, have invented a new, original, and ornamental Design for Lamp Casing, of which the following is a specification, reference being had to the accompanying drawing, forming a part thereof.

In the drawings Figure 1 is a top view; and Figures 2 and 3 are side views of a lamp casing embodying my new design.

I claim:

The ornamental design for a lamp casing as shown.

JOHN A. AMOS.
